The ornamental design of a spraying head, as shown and described.

DESCRIPTION

FIG. 1 is a perspective view of a spraying head according to my new design;

FIG. 2 is a front view of the spraying head shown in FIG. 1;
FIG. 3 is a right side view of the spraying head shown in FIG. 1;

FIG. 4 is a back view of the spraying head shown in FIG. 1;
FIG. 5 is a left side view of the spraying head shown in FIG. 1;

FIG. 6 is a top view of the spraying head shown in FIG. 1;
FIG. 7 is a bottom view of a spraying head shown in FIG. 1;

FIG. 8 is a perspective view of a spraying head according to another embodiment of my new design;

FIG. 9 is a front view of the spraying head shown in FIG. 8;
FIG. 10 is a right side view of the spraying head shown in FIG. 8;

FIG. 11 is a back view of the spraying head shown in FIG. 8;

FIG. 12 is a left side view of the spraying head shown in FIG. 8;

FIG. 13 is a top view of the spraying head shown in FIG. 8;
FIG. 14 is a bottom view of a spraying head shown in FIG. 8;

FIG. 15 is a perspective view of a spraying head according to another embodiment of my new design;

FIG. 16 is a front view of the spraying head shown in FIG. 15;

FIG. 17 is a right side view of the spraying head shown in FIG. 15;

FIG. 18 is a back view of the spraying head shown in FIG. 15;

FIG. 19 is a left side view of the spraying head shown in FIG. 15;

FIG. 20 is a top view of the spraying head shown in FIG. 15;
and,

FIG. 21 is a bottom view of a spraying head shown in FIG. 15.

The embodiment shown in FIG. 1 and FIG. 7 is essentially the same as the embodiment shown in FIG. 8 to FIG. 14, but with a slightly altered version of the top front. The embodiment shown in FIG. 8 to FIG. 14 is essentially the same as the embodiment shown in FIG. 15 to FIG. 21, but with a thinner center back portion as can best be seen comparing FIGS. 8, 10, 11 and 12 with FIGS. 15, 17, 18 and 19, respectively.
